(57) **CLAIM**

The ornamental design for the manual food processor, as shown and described.

DESCRIPTION

FIG. 1 is a top perspective view of the manual food processor of the present invention;

FIG. 2 is a front elevational view thereof;

FIG. 3 is a first side elevational view thereof;

FIG. 4 is a rear elevational view thereof;

FIG. 5 is a second side elevational view thereof; and,

FIG. 6 is a top plan view thereof.

The broken lines in the drawings illustrate the portions of the design that form no part of the claim.
